CONVEYER FOR MOVING TRUCKS OVER TRACKS

Walter A. Woodard, Cottage Grove, Oreg.

Application February 8, 1952, Serial No. 270,558

5 Claims. (Cl. 104—172)

1

This invention relates to conveyors for moving trucks over tracks and is particularly adapted to move trucks having stacked lumber thereon.

The primary object of my new and improved conveyor is to engage the undersurfaces of truck frames wherein a series of trucks are used in the conveying of lumber by conveyor chains without the use of lugs. The contact pressure of the chain is equal against the undersurface of each truck, thereby preventing the shifting of the trucks under the lumber while being moved.

Means is provided within my conveyor to apply an even pressure contact under each truck, regardless of the unevenness existing in the tracks.

Means is also provided for adjusting the pressure contact under the frames of the trucks.

Another object of my invention is the providing of a control for starting and stopping the movement of the conveyor, positioning the trucks at an exact location.

These and other incidental objects will be apparent in the drawings, specification and claims.

Referring to the drawings:

Figure 1 is a plan view of my new and improved conveyor for moving trucks.

Figure 2 is a side sectional view, taken on line 2—2 of Fig. 1.

Figure 3 is a wiring diagram illustrating the electrical motors and the controls for the operation of the conveyors.

Figure 4 is an end sectional view, taken on line 4—4 of Figure 1, illustrating the conveyor chain in contact with the trucks to be moved.

Figure 5 is a sectional view, the same as Figure 4, except that the conveyor chain is retracted from underneath the trucks.

Figure 6 is an enlarged detail fragmentary plan view of the conveyor chain raising and lowering mechanism.

Figure 7 is an enlarged fragmentary detailed sectional view, taken on line 7—7 of Figure 4.

Referring more specifically to the drawings:

The mechanism of my new and improved truck conveyor is mounted within the frame 1, consisting of longitudinal beams 2 and transverse beams 3 at their ends, having intermediate beams 4 for supporting the mechanism about to be described.

Running centrally and longitudinally of the frame 1 is a conveyor chain 5. The chain 5 is trained around the sprockets 6, which are journaled at 7 within the frame 8. The frame 8 primarily consists of a channel 9 running between the centers of the sprockets 6 throughout the entire length of the conveyor chain.

Running longitudinally and centrally of the channel 9 is a raised track 10, upon which the

2

rollers 11 of the conveyor chain ride, providing easy movement of the chain under the weight to be transported thereby. The channel 9 is supported at intervals throughout its length upon the cross beams 4 in the following manner.

Referring particularly to Figures 1, 4 and 5, it will be noted that the channel is located between vertical guides 12, which form part of the cross beams 4 permitting up and down movement of the channel.

Levers 13 are pivotally mounted to the cross frames 4 at 14. The channel 9 and the conveyor chain 5 are supported upon these levers by way of the connecting rods 15, the lower bifurcated ends 16 of the rods being pivotally connected at 17 to the levers 13, while the upper threaded ends pass through the supporting brackets 18 extending down from the channel 9 and forming part thereof.

Lock nuts 19 provide for vertical adjustment of height of the channel above the levers 13. Weights 20 are adjustably positioned on the end 21 of the levers. These said weights are adapted to pivot the levers about their pivot point 14, raising the channel 9 vertically for contacting the underside 22 of the truck frames 23A. The pressure under these frames will depend upon the position of the weights 20 in regard to the levers 13.

In Figures 1, 2 and 4, I illustrate the conveyor chain 5 in contact with the truck frames, but in Figure 5 I illustrate how the conveyor chain is retracted or lowered from under the truck frames. Running longitudinally of the frame 1 is a shaft 24, journaled within bearings 25 which are mounted to the cross frames 4. This shaft has arms 26 keyed thereto. These arms have rollers 27 journaled on their outer ends and adapted to contact the surface 28 of the levers 13, as best illustrated in Figures 4, 5 and 6.

The shaft 24 is revolved by the motor 29, speed reducer 30 by way of the chain 31. The arms 26 take either the position shown in Figures 4 or 5. In the position shown in Figure 5 the effect of the weight 20 is overcome by the fact that the arm 26 pivots the lever 13 about its pivot point 14, lowering the conveyor channel and chain disengaging it from the frames 23A of the trucks. The trucks operate on the tracks 32, the said tracks being mounted to the frames 1.

In Figure 2 I illustrate by broken lines the position of stacked lumber resting on the frame 23A of the trucks 23. In the drawings I have illustrated but two trucks. There could be any number of trucks depending on the type of lumber being handled.

The length of the frame 1 could be considerably longer than shown. It can be installed over straight line tracks, or it can be mounted within elevators used to raise and lower lumber.

I will now describe the operation of my new and improved conveyor. The trucks 23 support the lumber, indicated by the broken lines 33, are moved over the conveyor chain 5 by any means, as for instance another conveyor set up similar to the one shown or any other means. The position of the conveyor chain is shown in Figure 5. When switch 34 is closed, the motor 29 is started, and the solenoid 36 is energized which closes a circuit through the motor 29 by way of the main line 37, conductor 38, motor 29, conductor 39, switch bar 40 and back to the main line by way of the conductor 41.

When the switch bar 40 reaches the broken line position, the latch 42 drops behind the said bar, holding the same. When the motor starts is revolves the shaft 24 in the direction of the arrow, bringing the arms 26 to the position shown in Figure 4, at which time it is desired to stop the rotation of the shaft 24 and the arms 26. Cams 43 are fixedly secured to the shaft, referring to Figures 1 and 3. These cams are adapted to contact the arm 44 of the latch 42, tripping the same from behind the switch bar 40, allowing it to return to open position at which time the motor 29 will stop rotating the arms 26 in the position shown in Figure 4.

The weights 20 by being allowed to lower will apply a lifting pressure under the conveyor chain 5, which will bear against the cross frames 23A of the trucks 23. This pressure being equal under all of the trucks, due to the fact, in referring to Figure 1, it will be noted that there are a series of levers 43 throughout the length of the conveyor, each being controlled by a separate weight. The movement of the conveyor chain 5 is controlled by the motor 29, speed reducer 30, driving sprocket 47 which drives the chain 5.

The chain 5 has a reverse run 48 into the chain tightener unit 49. This motor is controlled through a switch, the operator being able to see the exact location of the trucks from this switch control.

Assume now the conveyor is disengaged from the trucks, the switch 34 is again closed, bringing the switch bar 40 to the broken line position, energizing the motor 29 revolving the shaft 24 and the arms 26. This will bring the arms from the position shown in Figure 4 with their rollers 27 down against the surfaces 28 of the levers 43, raising the weights 20 and lowering the conveyor chain 5. When the arms reach the point shown in Figure 5, one of the cams 43 on the shaft will contact with the lever 44 and latch 42, disengaging the switch arm bar 40 and stopping the motor 29. Any suitable type of limit switch could be used, I have merely illustrated a switch mechanism that can accomplish the result, mainly because the operator cannot see the raising and lowering mechanism, therefore it has to be stopped automatically at the proper point.

In the drawings I have illustrated a conveyor of relative short length, but ordinarily it would be much longer. The conveyor I have illustrated

is adapted particularly to be installed on elevators where a slight movement of the lumber is required in order to line the same up for absolute accuracy of movement.

The outstanding feature of my new and improved conveyor, is the fact that upward pressure is applied to the conveyor chain at many points. These pressures insuring equal contact at a number of various points against the under side of the trucks, preventing shifting of the trucks under the lumber, which of course is a desirable effect, where lumber is being fed into machines automatically.

What I claim is:

1. A conveyor mechanism comprising a frame including a pair of spaced tracks for supporting a mobile carriage and a plurality of cross-frames extending between said tracks, a pair of sprockets journaled between said tracks in longitudinally spaced relation, an endless chain trained around said sprockets with its upper run extending substantially parallelly between said tracks, means for driving said chain, an elongated guide for the upper run of said chain, a plurality of longitudinally spaced supports on said cross-frames and carrying said guide, means independently biasing each of said supports upwardly to elevate said guide and lift the upper run of said chain against a carriage on said tracks to advance the carriage along said tracks, and means simultaneously engageable with all of said supports and selectively operable to simultaneously depress and release said supports.

2. A conveyor mechanism as defined in claim 1 wherein said supports each comprise a lever pivotally mounted on a cross frame, a connecting rod between said lever and said guide, and means biasing downwardly the end of said lever opposite the lever pivot from said connecting rod, whereby said connecting rod is urged upwardly.

3. A conveyor as defined in claim 2 wherein said lever biasing means comprises a weight adjustably mounted on said lever.

4. A conveyor as defined in claim 3 wherein said support depressing means comprises a shaft extending longitudinally between said tracks, a plurality of cam elements on said shaft and each engageable with a lever opposite the lever pivot from said weight to swing said lever in opposition to said weight and lower said connecting rod and guide to retract said chain, and means for selectively operating said shaft to revolve said cam elements to simultaneously engage said levers to lower the guide and to simultaneously release said levers to raise the guide.

5. A conveyor as defined in claim 4 wherein said shaft operating means comprises motor drive means connected with said shaft, a limit switch in circuit with said motor drive means, said switch being manually operable to energize said motor drive means and having a control element, and a double cam on said shaft and engageable with said limit switch control element to deenergize said motor drive means.
